UNITED STATES PATENT OFFICE.

FERDINAND S. OPPENHEIM, OF NEW YORK, N. Y.

CONTAINER.

Application filed August 1, 1925. Serial No. 47,470.

This invention relates to improvements in packing and shipping boxes, or cases, and is particularly directed to a novel form of reinforced double walled container or carton 5 constructed preferably of corrugated paper board or the like material for use in packing and shipping delicate apparatus, such as radio sets, meters, typewriters, and the like.

An object of the invention is to provide an 10 improved container of the character described having each of the inner side walls constructed of reinforced sections to effectively protect and cushion the contents from sudden blows and contacts so as to prevent injury and damage 15 to the contents due to careless and rough handling during transportation.

Another object of the invention is to provide an improved packing and shipping box 20 of the character described having cushioning members for each wall of the box made in sections and arranged to effectively secure articles of asymmetrical cross-section against movement when packed in the box.

A further object of the invention is to provide 25 a container of the character described which is simple in construction, permits quick and easy assembly and packing of contents therein, is inexpensive to manufacture, and practical and efficient to a high degree for 30 the purposes described.

Other objects of this invention will in part be obvious and in part hereinafter pointed out.

The invention accordingly consists in the 35 features of construction, combinations of elements and arrangement of parts which will be exemplified in the construction hereinafter described and of which the scope of application will be indicated in the following claims.

In the accompanying drawing, in which is 40 shown one of the various possible illustrative embodiments of this invention,

Fig. 1 is a perspective view showing a packing and shipping box embodying the invention, parts of the box being broken away to 45 show the interior construction;

Figs. 2 and 3 are cross-sectional views taken on lines 2—2 and 3—3 respectively in Fig. 1;

Fig. 4 is a perspective view of a side cushioning member or partition liner forming 50 part or section of an inner wall of the box;

Fig. 5 is a perspective view of a cushioning insert or filler member; and

Fig. 6 is a perspective view of a packing and shipping box similar to Fig. 1 but showing 55 a modified arrangement of the partition liner sections.

Referring in detail to the drawing, 10 denotes an outer casing or shell of a packing and shipping box embodying the invention which may have any desired shape or design and 60 may be made of fibre board, card board, or the like material, but is preferably constructed of single or double corrugated paper board, the cellular structure of which has been found to add greatly to the cushioning effect for the 65 purposes described.

As seen in Fig. 1, the outer casing is of the usual collapsible construction to permit economical "knock down" shipment and comprises elongated side walls 11, end walls 12, 70 and cover flaps 13, 14, 15 and 16, all preferably formed of a single sheet of material, cut, creased, and folded to form the rectangular shaped shell 10, the cover flaps being adapted to fold inwardly to form the top and bottom 75 walls for closing the casing. When the flaps are folded into closed position, they may be held in place by any suitable means, as for example a strip of adhesive tape 17.

Partition liners or cushioning members 18 80 and 18^a are provided which are arranged against the side walls, end walls and bottom as shown in Figs. 1, 2 and 3. These may be substantially identical in construction and as is seen most clearly in Fig. 4 each is preferably formed of a single sheet of corrugated paper board, cut, creased and folded to form a rectangular shaped body portion 19, end walls 20 and side walls 21, said side walls 21 having flap extensions 22 which are bent to 85 extend within and adjacent the end walls 20 and held in position by suitable fastening means. The flap extensions 22 or other fastenings for the side and end walls, to retain them in their relative positions may be 90 omitted if desired, since it is apparent that when the members 18 are assembled within the casing 10 the structure is self-retaining. 95

It is to be understood that the shipping 100 box is of suitable dimensions to enable packing the article or articles therein so as to substantially fill the space marked A and that the liners 18 and 18^a are of proper size and shape and arranged to completely cover the 105 interior sides and bottom of the casing.

The liners 18 are arranged to serve as wall sections and are preferably made to extend only over a portion of each of the inner sides of the casing 10, two or more liners 18 being 110 arranged in either a horizontal or vertical row to entirely cover each of the said casing

sides as shown in Figs. 1 and 6 respectively. The top and bottom inner cushioning structure may also be formed of a plurality of liners 18^b and 18 respectively, arranged in 5 rows.

The top cushioning member 18^b preferably is made with outwardly extending flaps 20^a and 21^a which are arranged to overlie the upper side of the side liners 18 as shown in 10 Figs. 1, 2 and 3.

By constructing each of the sides of the inner casing walls of abutting sections, each section comprising a liner 18 as above described, an exceptionally strong and light 15 cushioning structure is provided since the abutting liner side walls 21 form transversely extending reinforcing ribs shown at 21^b between the inner and outer walls of the casing (see Figs. 1 and 6.)

20 Where the contents does not abut all the sides of the casing, cushioning inserts or filler members 23 are provided to fill the vacant spaces as shown in Figs. 1, 3 and 5. Each member 23 is preferably constructed 25 of a single sheet of corrugated paper board, cut, creased and folded to have a rectangular body portion 24, end walls 35, and side walls 36, said end and side walls having their respective edge portion 35^a and 36^a respectively 30 bent to extend inwardly, one end of each of said portions being positioned to overlap an end of an adjacent portion, and the other end of each portion arranged to underlie an adjacent portion (see Fig. 5). The member 23 35 thus constructed forms a highly effective cushioning structure and serves to support and hold the contents against accidental displacement.

For packing articles of asymmetrical cross- 40 sections such as an enclosing cabinet having a sloping side or other like objects, there is provided the liner 18^a which extends over the inner side portion of the casing over and abutting the said sloping side of the object 45 to serve as a bracing means therefor, as shown in Fig. 2. The liner 18^a is made wider than the adjacent lower liner 18 and as desired may be either of symmetrical substantially U-shaped or as shown in Fig. 2 may 50 have unequal sides 45 and 46, the longer side 46 being adapted to engage the sloping side of the cabinet.

In the practice of the invention, the side, 55 end, and bottom partition liners 18 are placed in position in the casing 10 and those abutting said bottom liners are held in place thereby as is clearly shown in Figs. 1, 2 and 6. Having arranged these liners in position with their body portions 19 spaced inwardly from 60 the various walls of the casing, the cabinet or other article to be packed is then lowered into place. The liner 18^a is then fitted into place with the corner edge portion thereof adjacent the longer side 46 abutting the sloping side of the cabinet and the cushioning 65

filler members 23 are inserted in the vacant spaces between the side of the cabinet and the body portion 19 of the adjacent liners as shown in Figs. 1, 3 and 6, thereby spacing and holding the cabinet a substantial distance 70 from the walls of the casing.

With these parts in position, the top cushioning members 18^b are inserted in the top opening of the casing, the body portion 19 of the members 18^b abutting the top side of 75 the cabinet, said members being dimensioned to the proper height to fill the space between the top side of the cabinet and the top of the casing. The cover flaps are then folded into position and the casing sealed in any suitable 80 manner as by means of a strip of adhesive tape 17.

It will thus be seen that there is provided a device in which the several objects of this invention are achieved and which is well 85 adapted to meet the conditions of practical use.

As various possible embodiments might be made of the above invention, and as various changes might be made in the embodiment 90 above set forth, it is to be understood that all matter herein set forth or shown in the accompanying drawing is to be interpreted as illustrative and not in a limiting sense.

Having thus described my invention, I 95 claim as new and desire to secure by Letters Patent:—

1. A packing and shipping box having inner and outer walls, the inner wall forming a receptacle spaced from the outer wall, said 100 receptacle adapted to receive articles of various cross-sectional shape, at least one side of the inner wall formed with abutting partition liner sections, one of said sections projecting into the receptacle adapted to engage 105 an asymmetrical side of the article packed for preventing movement thereof during transportation.

2. A packing and shipping box having an inner cushioning wall structure, the side of 110 said structure formed with abutting partition liner sections, one of said sections projecting beyond the others and adapted to engage an asymmetrical side of an article packed in said box for preventing movement thereof during 115 transportation.

3. A packing and shipping box having an inner cushioning wall structure, the side of 120 said structure constructed of a plurality of partition liners, one of said liners being of greater height than the others and adapted to extend into the packing space of the box for abutting the contents to prevent accidental movement thereof during transportation. 125

4. A packing and shipping box comprising an outer casing having a plurality of abutting separately removable partition liners arranged therein for each of the side walls of said casing, said liners forming a 130

reinforced supporting structure in the casing adapted to protect and cushion the enclosed contents against damage during transportation.

5. A packing and shipping box comprising an outer casing having a plurality of abutting separate partition liners arranged therein for each of the side walls of said casing, each liner being individually insertible
10 in and removable from the outer casing, said liners forming a supporting structure in the casing adapted to protect and cushion the enclosed contents against damage during transportation, the abutting side of said
15 liners forming transversely extending reinforcing ribs for said structure.

6. A packing and shipping box adapted to support the contents in spaced relation to the sides, at least one of the side walls thereof

having a plurality of partition members 20 forming a reinforced cushioning means between the side of the contents adjacent said wall and the casing, said members being unconnected to permit each to be individually inserted in and removed from the box. 25

7. A packing and shipping box adapted to support the contents in spaced relation to the sides, at least one of the side walls thereof having a plurality of abutting partition liners, the abutting sides of said liners forming transversely extending reinforcing means for spacing the side of the contents adjacent said wall from a side of the casing, said members being unconnected to permit each to be individually inserted in and removed from 35 the box.

In testimony whereof I affix my signature.

FERDINAND S. OPPENHEIM.
